ABSTRACT OF THE DISCLOSURE

Monitoring power consumption of A.C. motors driving the metering and booster pumps, to detect abnormal conditions. Meter relays are connected to each motor to actuate alarms when power consumption varies outside of pre-selected limits. This permits early detection of excessive or insufficient pack pressure, inadequate melt supply, etc.

This invention relates to a method and apparatus for melt spinning of polymers, wherein the power consumed by the pump motors is used to determine the condition of the spinning system.

In melt spinning of synthetic fibers it is customary to pump a metered stream of fiber forming viscous polymer through a spinning pack just prior to extrusion through a spinneret. Various abnormal conditions can occur in such a system, such as plugging of the filter media in a spinning pack, development of channels through the filter media, pack leaks, variation in supply of the molten polymer, etc. Early detection of these defective conditions permits substantially more efficient and economical operation of the spinning unit. One prior art approach to determining such abnormal operation is to mount a mechanical torque gauge on the pump drive shaft. However it is very difficult to keep mechanical gauges properly calibrated, and, since the gauge rotates with the pump shaft, it is difficult to read and could pose a safety hazard. It has now been discovered that abnormal operation can be more simply and reliably determined by monitoring the power consumed by the pump of a melt spinning apparatus.

Accordingly the primary object of the invention is to provide a method and apparatus for reliably and accurately detecting certain abnormal spinning conditions. A further object is to provide a method and apparatus of the above character wherein the detection is accomplished by monitoring the power consumed by the pump motors. Other objects of the invention will in part be obvious and will in part appear hereinafter.

For a more complete understanding of the nature and objects of the invention, reference should be had to the following detailed description taken in connection with the accompanying drawings, in which:

FIGURE 1 is a schematic vertical sectional view of an exemplary melt spinning apparatus according to the present invention, and

FIGURES 2 and 3 are graphs of pack pressure versus meter pump motor power requirement, and pack pressure versus spun denier, respectively, for a particular spinning apparatus.

FIGURE 1 illustrates a generalized melt spinning apparatus wherein polymer flake is introduced into an aperture 20 in the top of a heated block assembly 22. The flake is melted by heated fins 24 and falls as molten polymer into melt pool 26 beneath fins 24. Booster pump 28 is driven by alternating current motor 30, which may be of induction type, and is submerged in melt pool 26 and supplies molten polymer to distribution passage 32. Close-tolerance meter pump 34, driven by synchronous motor 36, has its inlet passage connected to receive the polymer in passage 32, and pumps a metered output stream into

2

chamber 38 for extrusion through spinneret 40. It should be understood that in actual practice several metering pumps would normally be supplied from distribution passage 32. The molten polymer extruded through spinneret 40 is illustrated as forming a plurality of filaments 42 which are solidified or cooled by conventional means (not illustrated) and gathered into yarn 44.

A filter or spinning pack 46 is mounted in chamber 38 above spinneret 40 to remove gel particles and the like from the molten polymer. Filter 46 also imparts desirable shear to the polymer just prior to extrusion, as is well known in the art. Filter 46 may be composed of layers of various grades of sand, stacked screens, sintered porous structures, or the like.

Synchronous motor 36 may be any of the conventional synchronous motor constructions. Thus it may have a permanent-magnet rotor, a D.C.-excited rotor, or the motor may be of reluctance synchronous design. Whatever the type synchronous motor selected, means 48 (illustrated as a wattmeter) are provided for detecting the power consumed by motor 36.

FIGURE 2 illustrates the power consumed by such a synchronous motor as a function of the pressure developed in chamber 38, for an exemplary embodiment of the invention. As illustrated, motor 36 consumed about 15 watts with filter 46 and spinneret 40 removed, and there is a substantially linear relationship between power consumed and the pressure in chamber 38 (pack pressure), so long as the pressure in passage 32 is reasonably constant. In normal operation, the pressure in passage 32 will be reasonably constant.

FIGURE 3 illustrates the relationship between spun denier and pack pressure, for an exemplary yarn count. The horizontal dotted lines indicate acceptable denier quality control limits. Therefore, for this particular yarn count the minimum spinning pressure is around 1700 p.s.i. (pounds per square inch) and the maximum spinning pressure is near 5800 p.s.i., corresponding to meter pump wattages of about 30 and 55 respectively.

During normal operation of the FIGURE 1 system, as filter 46 traps and removes gel or other impurities, the resistance presented by filter 46 slowly increases and therefore the pressure in chamber 38 goes up. This continues until the denier of the spun yarn decreases below acceptable quality control levels because of increased slippage in pump 34, or until a leak develops. If the filter is replaced before the pressure builds up to this critical level, a considerable reduction in production of off-grade or defective low denier yarn is achieved since the spinning unit may spin off-grade yarn for many hours before the defective condition is detected by actual measurement of the yarn denier. If relay contacts are added to meter 48 to form a meter relay, a simple alarm or light 49 may be activated whenever the meter pump wattage varies outside the predetermined limits of normal operation, thus detecting defective yarn as soon as it is spun without the necessity of visual monitoring of the meter.

In the usual construction booster pump 28 supplies more polymer to distribution passage 32 than is pumped by metering pump 34. In such a construction, booster pump 28 has a relief orifice on its output side, to discharge the excess polymer back to melt pool 26. On occasion this relief orifice becomes plugged and causes a sharp increase in pressure in passage 32. This reduces the pressure difference across meter pump 34 and causes an increase in spun denier. Conversely, if booster pump 32 suffers a loss of polymer supply due to a temporary lowering of the melt rate, the pressure in distribution passage 32 drops or becomes variable. This condition will result in production of low or variable denier yarn. Either of these conditions (plugging of the relief orifice or loss of polymer supply) causes substantial variations in the power con-

sumed by booster motor 30. Similar to meter 48, relay contacts may be added to meter 50, in order to actuate a light or alarm 52 when the power consumed by motor 30 varies outside a pre-determined range. Alarms 49 and 52 can be combined, if desired.

A comparison of the readings of wattmeters 48 and 50 can usually identify the type of abnormal condition. Thus if meter 50 maintains its normal reading while meter 48 indicates an abnormally high reading, the defective condition is an abnormal increase in the resistance of filter 46. If, on the other hand meter 50 reads an abnormally low wattage while meter 48 indicates a normal or low wattage, the failure is a loss of polymer supply to the booster pump 28. Other defective conditions are similarly indicated by other comparisons of meter readings.

It should be understood that the power measuring means 48 and 50 need not necessarily include a conventional meter as such, but could include other means responsive to the levels of power consumed by motors 30 and 36. Monitoring the power of the meter pump motor according to the invention is not restricted to metering pump supplied from melted polymer flake, but may be applied to metering pumps fed directly from a polymerizer. In any case where a plurality of spinning positions are to be monitored, it may be desirable to provide a scanning mechanism whereby a single power-measuring means is connected, as by a stepping switch, to sequentially measure the power consumed in several motors. Provision of a suitable scanning mechanism is well within the scope of one skilled in the art.

The invention has proved to be of substantial economic significance. In one particular extended comparison with control spinning, application of the invention permitted the reduction of low denier yarn by 62%, reduction of pack leaks by 56%, and provided a significant improvement in overall denier uniformity.

It may be seen that the invention as above disclosed provides a substantial improvement in the art of spinning of artificial fibers. The apparatus necessary for practice of the invention is simple and reliable, and provides economic advantages greatly in excess of the cost of the additional apparatus. If separate power measuring means are provided for the meter pump motor 36 and the booster pump motor 30, the cause of failure of the unit can be determined with considerable assurance before the equipment is disassembled for repair. In addition, the power measuring system herein disclosed permits each unit to be operated until the pack pressure actually increases to an unsatisfactory level, rather than disassembling all units after some arbitrary time in service has elapsed.

It will thus be seen that the objects set forth above, among those made apparent from the preceding description, are efficiently attained and, since certain changes may be made in carrying out the above method and in the construction set forth without departing from the scope of the invention, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a spinning process wherein a meter pump supplies polymer through a filter media, and wherein said pump is driven by a synchronous motor, the improvement comprising in combination:

(a) selecting said filter media so that said motor initially consumes power within a pre-determined range of wattage,

(b) and detecting when said power varies outside said pre-determined range of wattage.

2. In apparatus for melt spinning filaments from a molten polymer, wherein a synchronous motor drives a meter pump for supplying molten polymer through a spinning pack to a spinneret for extrusion to form filaments, the combination therewith of:

(a) means for measuring the power consumed by said motor,

(b) and means, responsive to variations of said power outside a pre-determined range of variations, for detecting abnormal operation of said apparatus.

3. In apparatus for melt spinning filaments from a molten polymer, wherein an alternating current drives a booster pump for supplying molten polymer to a meter pump, the combination therewith of:

(a) means for measuring the power consumed by said motor,

(b) and means, responsive to variations of said power outside a pre-determined range of variations, for detecting abnormal operation of said apparatus.

4. The process defined in claim 1, further comprising:

(a) supplying polymer through a distribution passage-way to the inlet of said meter pump from a booster pump driven by a further motor; and

(b) detecting when the power consumed by said further motor varies outside a further predetermined range of wattage.

5. The process defined in claim 4, further comprising normally re-circulating a portion of the output of said booster pump to the polymer input supply for said booster pump.
